(57) **CLAIM**

I claim the ornamental design for a wireless telephone base unit, as shown and described.

DESCRIPTION

FIG. 1 is a top perspective view of a first embodiment of a wireless telephone base unit of the present invention;

FIG. 2 is a front view thereof;

FIG. 3 is a top view thereof;

FIG. 4 is a rear view thereof;

FIG. 5 is a first side view thereof;

FIG. 6 is a second side view thereof;

FIG. 7 is a bottom view thereof;

FIG. 8 is a top perspective view of a second embodiment of a wireless telephone base unit of the present invention;

FIG. 9 is a front view thereof;

FIG. 10 is a top view thereof;

FIG. 11 is a rear view thereof;

FIG. 12 is a first side view thereof;

FIG. 13 is a second side view thereof; and,

FIG. 14 is a bottom view thereof.

The ornamental design which is claimed is shown in solid lines in the drawings. Any broken lines in the drawings are for illustrative purposes only and form no part of the claimed design.
